UNITED STATES PATENT OFFICE.

WESLEY G. NICHOLS, OF CHICAGO HEIGHTS, ILLINOIS, ASSIGNOR TO AMERICAN MANGANESE STEEL COMPANY, OF CHICAGO, ILLINOIS, A CORPORATION OF MAINE.

DIPPER TOOTH.

Application filed December 30, 1918. Serial No. 268,817.

To all whom it may concern:

Be it known that I, WESLEY G. NICHOLS, a citizen of the United States, residing at Chicago Heights, in the county of Cook and State of Illinois, have invented certain new and useful Improvements in Dipper Teeth, of which the following is a specification.

My invention relates to dipper teeth for dredge buckets and particularly to a novel 10 way of making the same.

In making dipper teeth and points therefore, it has been common practice to make these of cast metal, forming the point separately from the base or tooth portion and 15 providing means so that the points may be removably connected to the base portion for renewal when worn without having to take the base portion off the dipper. Since alloy steel has been used in the manufacture of 20 dipper teeth and points, heat treatment has played an important part in the manufacture of such articles. Whenever manganese steel is used to make dipper teeth and points, heat treatment is very necessary. In my practice 25 I have discovered that the size and shape of the castings are important when it comes to the matter of heat treatment. In making dipper teeth or base portions of the usual type it is necessary that comparatively thin 30 sections adjoin thick sections. To prevent "mis-runs", that is, to have the thin sections of correct size and dimension, it is necessary that the molten metal be at such temperature that the thin sections will be filled with metal.

Oftentimes the temperature necessary to make the thin sections is too high for the thick sections, the thin sections cooling more rapidly than the thick, in which instance, the impurities are drawn to the metal in the 35 molten or semi-molten state, thus causing an excess of impurities to be segregated in a comparatively small area which segregation is the cause of great weakness in the finished casting and failure thereof invariably results at the place where the segregation is most prominent.

In heat treatment of cast sections difficulties are experienced in properly treating heavy sections. Unless the heat penetrates 40 the sections and is held long enough to dissolve the carbide along the austentic grain boundaries—in the case of manganese steel—weakness occurs which results in failure of the castings when put in service. Experience has shown that dipper teeth designed 45

for heavy service are very rigid even when made of manganese steel and often cannot absorb the shocks imparted thereto, the result being that the teeth or the base castings break.

One of the objects of my invention is to overcome the above recited and other recognized objections to dipper teeth and points.

Another object is to provide dipper teeth of alloy steel so made as to be properly heat 65 treated and at the same time to permit manufacture of larger and heavier teeth than can be made under the present practice especially as regards heat treatment.

A further object is to make dipper teeth 70 formed of a plurality of relatively thin sections fastened together to make teeth of varying thicknesses as requirements demand and which will be uniformly heat-treated throughout.

A still further object is to improve dipper teeth for successful commercial use.

Generally speaking I accomplish the objects of my invention by providing laminated base portions and points, the parts being 80 suitably secured together to form unitary articles.

The above recited and other objects will be apparent from an observation of the drawings, wherein—

Figure 1 is a top plan view partially in section of a dipper tooth and point made in accordance with my invention.

Figure 2 is a side elevation of a tooth shown in Figure 1.

Figure 3 is a vertical section on line 3—3 of Figure 2, and

Figure 4 is a section on line 4—4 of Figure 2.

The dipper tooth of my invention includes 25 a point and a base each of which is formed of a plurality of comparatively thin sections preferably of substantially uniform thickness. I have chosen to show the tooth formed of three such sections indicated by the reference characters 5, 6, and 7. The length, shape and size of these several sections may be made to conform to a single standard pattern or to any arrangement of patterns which may be useful in forming teeth of the desired shape, size and strength. In elevation the sections are similar to those shown in Figure 2 which is the general outline of a dipper tooth base portion. The sections 5, 6 and 7 are cast separately and separately subjected to heat treat- 110

ment, the result being that a casting is formed of a uniform thickness so that the heat treatment is uniform throughout; that the finished section is homogeneous; and that there is no segregation at any point therein to weaken the base. The sections are assembled in edgewise relation with the flat surfaces in contact as shown and secured together preferably by transversely extending rivets 8, the heads of which are preferably countersunk so as to be flush with the side faces of the base. The middle section 6 is provided with a series of vertically extending apertures 9 through which the bolts or rivets pass to secure the base to the dipper front as is common practice. Referring to Figure 3, it will be noted that the sections 5, 6 and 7 are substantially of equal thickness and the rivet holes 9 pass through the center line of the section 6 so that walls of uniform thickness are made at the sides of the apertures all of which uniformity tends to permit a better heat treatment in that the heat may pass evenly around and through all of the several sections.

With a laminated base formed in accordance with my invention I might employ a point made of a single casting or forging or one made of a plurality of sections similar to the base portion. In the drawings I have shown a point made of three sections 10, 11 and 12, secured together by rivets 13 as shown. The sections 10 and 12 are provided with recesses 14 for cooperation with dove tail projections 15 on each side of the middle section 11. This arrangement has been provided so that all tendency of the several sections to separate will be prevented by reason of the dove tailed arrangement, without having to depend on the rivets or the like for preventing separation of the several sections. It will therefore be observed that the only function served by the rivets in the points is to prevent relative longitudinal displacement of the various sections going to form a single point and that tendency for lateral separation is prevented by reason of the novel dove tailed arrangement shown. If it were desired to form a point of more than three sections this could be accomplished by displacement of the several sections providing as many co-operating lugs and recesses as the number of sections required.

It will be readily observed that by this method of making dipper teeth and points I am not limited in size in any respect due to any present restriction by reason of casting alloy steel and subjecting the castings to heat treatment. The only limit to size is that of use to which the teeth are to be applied. It may be readily observed that the thickness of the teeth and points is not limited by a single casting as many or as few sections may be fastened together as is need-

ed to form a base either narrow or wide. In a similar manner the point may be made to conform to the tooth portion thus reducing considerably the number of patterns necessary in the foundry which immediately reduces the cost of manufacture of these parts.

While I have described more or less precisely the details of construction of my invention, I do not wish to be understood as limiting myself thereto, as I contemplate changes in form and proportion of parts and the substitution of equivalents as circumstances may suggest or render expedient, without departing from the spirit of my invention.

I claim:

1. A dipper tooth base comprising a plurality of relatively thin sections of substantially uniform thickness and similar shape, with the flat sides of the sections secured together so that when said base is in position on a dipper body the sections will be in edgewise relation with respect to said body.

2. A dipper tooth base comprising a plurality of relatively thin sections of substantially uniform thickness and similar shape, with the flat sides of the sections secured together so that when said base is in position on a dipper body the sections will be in edgewise relation with respect to said body, said sections having interfitting members to prevent separation of the same.

3. A dipper tooth base comprising a plurality of relatively thin sections of substantially uniform thickness and similar shape, with the flat sides of the sections secured together so that when said base is in position on a dipper body the sections will be in edgewise relation with respect to said body, and means for preventing displacement of the several sections.

4. A dipper tooth base comprising a plurality of relatively thin sections of substantially uniform thickness and similar shape, with the flat sides of the sections secured together so that when said base is in position on a dipper body the sections will be in edgewise relation with respect to said body, certain of said sections having openings therethrough to receive means for attaching said base to a dipper body.

5. A point for dipper teeth including a plurality of relatively thin sections of substantially uniform thickness secured together with the flat sides thereof in contact, said sections being arranged to lie in edgewise position when said point is secured in position on a dipper body.

6. A point for dipper teeth including a plurality of relatively thin sections of substantially uniform thickness secured together with the flat sides thereof in contact, said sections being arranged to lie in edgewise position when said point is secured in

position on a dipper body, and said sections having interfitting members to prevent separation of the several sections.

7. A point for dipper teeth including a plurality of relatively thin sections of substantially uniform thickness secured together with the flat sides thereof in contact, said sections being arranged to lie in edgewise position when said point is secured in position on a dipper body, and means for preventing displacement of the sections relatively to one another.

8. A dipper tooth point made up of a plurality of relatively thin sections of substantially uniform thickness secured together with the flat sides thereof in engagement, the sections having interengageable mem-

bers to prevent displacement thereof, and means for attaching said point to a dipper body in such position that the sections will be in edgewise position with respect to said body.

9. A dipper tooth adapted to be secured to a dipper body and having a point comprising a plurality of sections arranged side by side on edge to the dipper body, dove tail connections between said sections, and transverse means passing through said dove tail connections for securing the sections together.

Signed at Chicago Heights, Ill., this 21st day of December, 1918.

WESLEY G. NICHOLS.
